UNITED STATES PATENT OFFICE.

CHARLES E. BONINE, OF MELROSE PARK, AND HENRY W. STAUFFER, OF MANHEIM,
PENNSYLVANIA, ASSIGNEES TO JOHN H. MOSEMAN, OF LANCASTER, PENNSYLVANIA.

MILK-CAN-WASHING MACHINE.

Application filed May 21, 1917. Serial No. 169,840.

To all whom it may concern:

Be it known that we, CHARLES E. BONINE, of Melrose Park, in the township of Cheltenham, county of Montgomery, and State of Pennsylvania, and HENRY W. STAUFFER, of Manheim, in the county of Lancaster and State of Pennsylvania, have jointly invented certain new and useful Improvements in Milk-Can-Washing Machines, whereof the following is a specification, reference being had to the accompanying drawings.

The invention relates more particularly to a washing machine which is adapted for washing, thoroughly sterilizing and drying milk cans or the like.

An object of the invention is to provide a machine of the above character, having a washing station, a rinsing station, a sterilizing station, and a series of drying stations to which the can is presented in succession, so that it may be thoroughly cleansed and dried in an efficient manner and in a comparatively short time.

A further object of the invention is to provide a machine of the above character wherein the inside of the can is thoroughly washed and scoured with brushes which are caused to rotate and which are carried against the inner surface of the can by centrifugal force, the brushes being returned to their normal position by springs.

A still further object of the invention is to provide a machine of the above character, wherein the brushes for scouring the inner surface of the cans are carried by a single rotating pipe, which also serves as a means for supplying the washing water to the inside of the can.

A still further object of the invention is to provide a washing device of the above character, wherein the washing water is supplied by means of a steam injector or siphon, the control of the washing water being through the means of a quick-operating valve which is opened by hand, and which is closed automatically on the starting of a conveyer for shifting the cans from one station to another.

A still further object of the invention is to provide a machine of the above character, wherein a conveyer presents the washed cans first to a rinsing station, thence to a sterilizing station, and thence to a series of drying stations, said conveyer being manually started and automatically stopped

when the cans are properly positioned relative to the respective stations.

A still further object of the invention is to provide a washing machine for milk cans of the above character, which is so constructed that the can cover may be carried along with the can, simultaneously rinsed, sterilized and dried.

These and other objects will in part be obvious and will in part be hereinafter more fully disclosed.

In the drawings which show by way of illustration one embodiment of the invention, Fig. I, is a front view of a machine embodying our improvements, the enclosing cover for the rinsing, sterilizing and drying stations being removed.

Fig. II, is a view partly in plan, and partly in section of a portion of the machine.

Fig. III, is an end elevation of the machine, as viewed from the washing end thereof.

Fig. IV, is a detail showing the controlling cams for shifting the clutch which controls the rotation of the cleaning brushes.

Fig. V, is a view in top plan of the supporting table, the tank at the washing station, and the supply tank for supplying the washing water and the rinsing water, together with the pipe connections therefor, and also the pipe connections for the steam.

Fig. VI, is an enlarged longitudinal vertical sectional view through the machine, indicated by the arrows VI, VI, in Fig. V.

Fig. VII, is a view partly in section and partly in side elevation showing the means for raising and lowering the can, and a portion of the means for rotating the cleaning brushes.

Fig. VIII, is a horizontal sectional view showing the can in position for washing, the section being taken on the line VIII, VIII, of Fig. IX.

Fig. IX, is a view partly in side elevation and partly in vertical section of the parts shown in Fig. VIII.

Fig. X, is a vertical sectional view through the washing mechanism, said section being taken on the line X, X, of Fig. VIII, and one of the washing brushes of each set being displaced to the plane of section.

Fig. XI, is a vertical sectional view through the machine on the line XI, XI, of Fig. II.

Fig. XII, is a vertical section through

the tank containing the washing water, and also through the tank for supplying a soda solution thereto, and showing the controlling means, whereby the solution is fed to the 5 tank containing the washing water.

Fig. XIII, is a view partly in side elevation and partly in vertical section showing the controlling means for controlling the supply of hot air to the cans.

10 Fig. XIV, is a view partly in plan and partly in horizontal section, showing in part the controlling devices for controlling the conveyer and the steam valve.

Fig. XV, is a side view of the same.

15 Our improved washing machine is especially adapted for washing milk cans or the like, and includes broadly a series of stations for treating the cans with fluid, comprising a washing station, where the 20 cans are initially washed and scoured, a rinsing station, where the cans are thoroughly rinsed, a sterilizing station, where the cans are submitted to the action of steam for thoroughly sterilizing the same, and a 25 series of successive drying stations, where the rinsed sterilized cans are subjected to warm air for drying.

At the washing station, there is a series 30 of rotating brushes, carried by a single rotating pipe, vertically disposed and supplying the washing water for the cans. The can is inverted and placed over these brushes. The can is held from rotation and is raised and lowered by manually controlled arms carrying brushes which engage the outer side walls of the can. The 35 brushes engaging the interior of the can are mounted so as to be moved out into contact with the can through the centrifugal force acting on the same, and they are returned to normal position by springs. After the can has been thoroughly washed, it is then presented by hand to the rinsing station. The can remains inverted on the 40 supporting table while it is being rinsed and is carried along the supporting table by traveling devices so that the can may be presented successively to the rinsing station, thence to the sterilizing station, and thence to the drying stations above referred to.

An endless conveyer or carrier for shifting the can from one station to another is 45 manually started and is automatically stopped so that as soon as the can is properly positioned relative to the operating station, the carrier stops. The washing water and also the rinsing water is drawn from the supply tanks by steam injectors 50 which force the water through the pipes to the proper places, for washing and for rinsing, and thus serve as the sole means for supplying the washing water to the cans.

The steam which conveys the water is 55 controlled by a quick-action valve which is

manually opened and which is automatically closed when the carrier is started to shift the can from one station to another.

Referring more in detail to the drawings, my improved washing machine consists of a main supporting frame 1, which may be of any desired shape and construction for supporting the various members of the machine. The washing station is indicated at W, in Fig. II, of the drawings, and as shown therein, said station is at the left hand end of the frame 1. Mounted in suitable bearings is a vertical rotating shaft 2. This vertical shaft 2, is in the form of a pipe, and said shaft extends well up above its supporting bearing which is indicated at 3. Mounted on the shaft 2, is a fixed collar 4. Pivoted secured to this fixed collar 4, are three brushes 5, 5, which are particularly adapted for engaging the mouth of the milk can. The milk can is shown as inverted and as engaging these brushes in Fig. X, of the drawings, where said can is indicated at C. The brushes 5, 5, are connected at their lower ends to links, 6, 6, which, in turn are pivoted to a collar 7, free to move on the shaft 2. A spring 8, coiled about the shaft engages the collar 7, at its lower end and engages a fixed collar 9, at its upper end. This spring only 90 forces the collar 7, downwardly into engagement with a fixed collar 10, and holds the brushes drawn inwardly to their extreme inward position.

As the shaft 2, rotates, the centrifugal 100 force acting on the brushes 5, 5, will force the lower ends of same outwardly, compressing the spring 8, and this causes the brushes to engage the inner wall of the mouth of the can. Located above the 105 brushes 5, 5, are three brushes 11. These brushes are equally spaced angularly about the shaft and are similarly supported.

Each brush is pivoted adjacent its lower end to a link 12, which in turn is pivoted 110 to a fixed collar 13, carried by the shaft 2.

To each link 12, is pivoted a double link 14. These links 14, are pivoted to a sliding collar 15. A spring 16, is located between the collars 13, and 15, and normally 115 forces the collar 15, upwardly drawing the lower ends of the brushes inwardly away from the walls of the can.

We have provided a link 17, for each brush 11. This link 17, has a pin 18, sliding freely in a slot 19, in a bracket attached to the brush. The lower end of the link 17, is pivoted to a collar 20, which is fixed to the shaft 2. A spring 21, is pivoted at its lower end to the link 17, and at its upper end to a fixed collar 22, carried by the shaft 2. There is a spring 21, for each link 17. These springs normally tend to draw the upper ends of the brushes 11, inwardly. From the above it will be apparent that 120 125 130

each brush is mounted so as to move independently at its upper and lower ends, and the centrifugal force acting on the brush will carry it outwardly against the inner surface of the can. When, however, the shaft stops rotating, the spring 16, acting on the collar 15, will draw the lower ends of the brushes inwardly. The springs 21, will also draw the upper ends of the brushes inwardly.

Mounted on one of the brackets adjacent to the upper end of the brushes is another brush, indicated at 23, which is adapted to engage the bottom of the can. This brush is pivoted at 24, to the bracket, and is provided with a stop 25, which is adapted to engage the bracket and normally hold the brush 23, substantially horizontally. From the above it will be apparent that the can may be thoroughly scoured or cleaned on the inner face thereof by the brushes referred to, and the washing water which is charged with a soda solution is conveyed to the brushes and the inner walls of the can through the shaft 2, which, as above noted, is in the form of a pipe, and which has a nozzle 26, at its upper end.

The can is supported and held from rotation, and raised and lowered by two clamping arms 27, and 28. The semi-cylindrical sections 29, 29, are bolted to arms 27, and 28, and these sections which extend throughout the greater length of the can, are provided with vertically arranged brushes 30, 30, and 31, 31. The arm 27, is formed integrally with the sleeve 32. This sleeve is splined on a shaft 33, so as to turn with the shaft, but said sleeve is free to move endwise on the shaft. The shaft 33, (see Fig. VII), is mounted to turn in bearings 34, and 35, the bearing 35, being carried by the frame of the machine and the bearing 34, being carried by the bracket 36, bolted to the frame of the machine, and extending upwardly therefrom. The arm 28, is formed integrally with the sleeve 37, which is free upon a shaft 38, and this shaft 38, is mounted in the bearing 39, carried by the bracket 36, and in a bearing 40, carried by the frame. The sleeves 32, and 37, are provided with meshing segmental gears 41, and 42, respectively. The sleeves 32, and 37, are also provided with projecting arms 43, and 44, respectively. The spring 45, is connected to the outer ends of the arms 43, and 44, and this spring normally tends to hold the arms 27, and 28, forced inwardly so as to grip the can. The shaft 33, carries an arm 46, at its lower end, and this arm is pivotally connected to a link 47, see Fig. III. The link 47, is pivoted at its other end to a rocker 48, which is freely mounted on the shaft 49. This rocker 48, has its free arm terminating in a treadle 50, for the foot of the operator.

When the operator places his foot on this

treadle 50, and presses downwardly, the rocker 48, through the link 47, will cause the shaft 33, to move in a counter-clockwise direction, and this, through the segmental gears 41, and 42, will operate the shaft 38, 70 and thus cause the arms 27, and 28, to swing away from the can, and release the same. From the above, it will be apparent that the arms 27, and 28, may be so controlled by the treadle 50, and the spring 45, as to grip 75 the can and prevent it from rotating, or lightly engage the can permitting the same to rotate with the inner brushes. This enables the can to be rotated through contact with the inner brushes, and the outer 80 brushes to scour the outer surface of the can.

A perforated pipe 51, is carried by the semi-cylindrical section 29, and this perforated pipe is suitably connected with the 85 washing water as will be described herein-after. Through this pipe the washing water is thrown against the surface of the can and it is thoroughly washed by the aid of the brushes, as above described. The brushes 90 52, and 53, may also be provided, for washing the lower part of the body of the can and these brushes are carried by depending arms 54, and 55, respectively, which are bolted to the arms 27, and 28, respectively, 95 see Fig. IX.

The sleeves 32, and 37, may be moved up and down on their supporting shafts by means of a bracket 56. This bracket 56, (see Fig. VII), serves as a supporting means 100 for the sleeves 32, and 37. A chain 57, is connected to a lug 58, attached to the bracket 56. This chain runs over a sprocket wheel 59, and meshes therewith. A counter-weight 60, attached to the other end of the chain 105 serves as a means for counter-balancing the weight of the can, and the supporting parts therefor. The sprocket wheel 59, is moved through a part of a rotation by means of a link 61, which is pivoted at 62, to the 110 sprocket wheel and which is also pivoted at 63, to an arm 64, fixed to the shaft 49. The lever 65, is also fixed to the shaft 49, and serves as a means for oscillating the arm 64. The link 61, is formed in sections. The 115 upper section of the link carries a guide 66, into which the lower section of the link extends. The lower section of the link is formed so as to slide in this guide. A spring 68, is interposed between a head on said 120 lower section of the link and the lower end of the guide 66. This spring permits a certain amount of lost motion and together with the guide permits the operator to shift the lever 65, to accomplish certain results 125 hereinafter specified, without moving the can.

It will be apparent from the above description that when the lever 65, is swung to the right, as viewed in Fig. III, the lower 130

section of the link 61, will gradually slide up in the guide and finally striking the upper end of the guide 66, will rotate the sprocket wheel and raise the can. A movement of the lever 65, in the opposite direction will lower the can onto the inner brushes. The shaft 2, carries a bevel gear 69, at its lower end, which meshes with the bevel gear 70, on the shaft 80. This shaft 10 80, carries a clutch having an inner member 81, which is free on the shaft and which carries a sprocket wheel 82, co-operating with the sprocket chain 83, which, in turn co-operates with the sprocket wheel 84, on 15 the main shaft which is driven by the belt wheel 85, see Fig. II.

The outer member of the clutch indicated at 86, is splined to the shaft 80, and has a free endwise movement thereon. A yoke 20 lever 87, is connected to this member 86, of the clutch for shifting the same. A link 88, is pivoted to this yoke lever at one end and the other end of said link is pivoted to a rocker 89. A spring 90, fastened at one 25 end to the frame and at its other end to the yoke lever 87, normally tends to move the clutch members into engagement and to cause the shaft 2, to be driven from the main shaft. Fixed to the shaft 49, is a controlling 30 plate or cam-plate 91, whose acting face cooperates with the roller 92, on the rocker 89. The cam face is shaped so that when the parts are in the position shown in Figs. III, and IV, the spring 90, shifts the 35 clutch members, so as to bring them into engagement. When, however, the plate 91, is swung in a clock-wise direction, from the position shown in Fig. IV, the outer portion of the cam surface will engage the 40 roller 92, and separate the clutch members and hold them separated so long as the roller is on this high level of the controlling surface.

The controlling cam 91, is so proportioned 45 that the clutch will be shifted to rotate the brushes immediately after the handle 65, is moved to lower the can. This arrangement allows every portion of the interior 50 of the can to be thoroughly subjected to the action of the brushes, and also affords a wide range of movement between the can and brushes without disengagement of the clutch.

As soon as the can is fully raised to its 55 upper position after the brushing is completed, the shaft 80, will cease rotation and permit the brushes to be disengaged from the inner surface of the can. After it has been raised to the proper position for 60 removal, then the operator by depressing the treadle 50, separates the arms 27, and 28, and releases the same from the grip upon their can. Extending about the lower part 65 of the can is a casing 93. This casing is

mounted on the frame and serves to collect 65 the washing water which passes off from the casing through the suitable drain opening 94, in the bottom thereof. To facilitate the removing of the can we have provided an opening 95, through the side wall of the 70 casing 93, and the casing extends outwardly in the region of the opening and is also provided with a baffle 96. The baffle 96, is provided in the bottom of the casing at such location that wash water which is thrown 75 from the outer surface of the can will be collected behind the baffle. This wash water is for the purpose of wetting a hand brush which is kept in the pool of water so as to be readily accessible to the operator 80 and used to wash portions of cans of such configuration as not to be reached by the brushes provided regularly upon the machine.

The main supporting frame 1, carries a 85 supporting table or way on which the cans rest in inverted position while they are being rinsed, sterilized and dried. Extending from end to end of the table are a series of supporting members in the form of rods 90 97. The cans are removed one at a time from the washing apparatus and are placed on these rods 97, inverted as above noted. Passing along the upper surface of the table is an endless conveyor which consists 95 of two travelling chains 98, and 99, which are connected at intervals by approximately horizontal cross pieces 100. These endless chains run over suitable sprocket wheels on the shaft 101, at one end of the machine; and suitable sprocket wheels 102, at the other end of the machine. The rods 97, are bent 100 downward at their free ends as clearly shown in Fig. VI, of the drawings. Cross pieces 100, are of angular cross section as 105 clearly shown in Fig. VI, and formed with a V-shaped recess 103, which is adapted to receive the neck of the inverted can and slide the same along the supporting rods 97. The cross pieces 100, are also provided with 110 a second V-shaped recess 104, which is adapted to engage the cover and slide it along the rods 97, at the other side of the supporting table. It will thus be seen that the cover for the can and the can itself are 115 simultaneously moved along the supporting rods from one end to the other of the table.

The rinsing station is indicated at R, in 120 Figs. II, V, and VI, of the drawings. The interior of the can only is rinsed and this is 125 accomplished by means of a shower of rinse water from a nozzle 105. This rinsing nozzle is located at the end of the pipe 106, which supplies the rinsing water. At the rinsing station the cover is washed by means of a nozzle, 107, connected to the pipe 106. A circular spray 108, is also connected with 125 said pipe 106, and an overhead shower 109,

which is connected through the pipe 110, to the pipe 111, and the pipe 106, is also connected to this pipe 111.

In Fig. II, of the drawings, we have indicated at S, the sterilizing station. The interior of the can is subjected to live steam through a nozzle 112. This nozzle is connected to a pipe 113. The cover is also subjected to steam through a similar nozzle 114, a circular nozzle 115, and an overhead shower 116. These nozzles and the steam shower are all connected with the pipe 113. The steam is led to the machine from any suitable source of supply through the pipe 117, (see Fig. VI). The pipe 117, has a quick-action valve 118, therein. This pipe 117, connects with the pipe 119, and the pipe 119, is connected with the pipe 113, so that when this quick-action valve 118, is opened 20 steam passes through the pipe 119, and the pipe 113, and thoroughly sterilizes the rinsed can and the rinsed and washed cover.

The rinse water is led from a suitable source of supply to a tank 120. The pipe 121, is connected with this tank. The pipe 122 (controlled by a hand valve 123) is connected to a steam injector located at 124, and connected with the pipe 121 through a pipe connection 125. The pipe 111, connects with 30 this steam injector or siphon. The steam passing from the pipe 119, through the steam injector will draw the rinse water from the tank and convey the same through the pipe 111, to the pipes 110, and 106, and thus force the rinse water out through the nozzles and the shower onto the parts to be rinsed.

It will be understood that as long as the steam continues to flow, the rinse water will 40 be thrown against the can and the cover. The wash water is fed to the storage tank 126, from a suitable source of supply and the valve controlling the inlet of the water is controlled by a float 127. A similar float-controlled valve is used in the rinsing tank. Mounted on top of the washing tank is a small tank 128, for the soda solution to be used in connection with the washing. There is a port 129, leading from the tank 128, to 50 the tank 126, and a valve 130, operates to close this port. This valve is formed at the lower end of a rod 131, which extends up through the tank 128, and a spring 132, bearing on the collar 133, attached to the rod 131, normally forces the valve downwardly so as to close the port 129. This rod 131, is pivoted at 134, to a lever 135, which runs on a controlling cam 136, rotated once for each rotation of the shaft 101. This controlling cam has a cam projection 137, which lifts the lever 135, once during each rotation of the shaft and while the lever is lifted the valve-controlled port 129, is opened and this allows a certain amount of soda solution to 60 pass down into the wash water.

A pipe 138, leading from the tank 126, for the wash water connects with the pipe 139, which in turn is connected to a steam injector or siphon 140. This steam injector or siphon 140, is connected through a pipe 70 141, with steam pipe 119, and this connection is controlled by a hand valve 142. A pipe 143, is also connected with the steam injector or siphon, and this pipe 143, leads to a pipe 144, which is connected with the 75 hollow shaft 2, so as to supply the same with the wash water. It is also connected through the pipe 145, with the pipe 51, which supplies the outer surface of the can with wash water. This pipe 145, includes 80 a flexible section which permits the milk can to be moved up and down during the washing thereof.

The steam from the pipe 119, entering the steam injector 140, draws the wash water 85 from the tank 126, and conveys the same to the interior and exterior of the can at the washing station. It will be noted that as long as the steam continues to flow, the can will be subjected to clean washing water 90 both interiorly and exteriorly. All the pipes above named may be provided with drain cocks so that the entire system may be drained of water whenever desired.

After the cans have been thoroughly 95 rinsed and sterilized they are then conveyed to the drying stations, which are indicated at D, D, in Fig. II, of the drawings. Directly below the table at the right hand end thereof, is a chamber 146. Air is delivered 100 to this chamber 146 from the pipe 147, which is connected to a blower indicated at 148.

Air is taken from the chamber 146, 105 through a pipe 149, which connects with a vertical pipe 150, and this vertical pipe connects with a manifold 151, extending along the side of the machine. A cross pipe 152, at each drying station, connects with the manifold 151, and each cross pipe has an 110 outlet opening 153, for the can, and an opening 154, for the cover. Located within the vertical pipe 150, is a valve indicated in dotted lines 155, in Fig. XIII of the drawings. This valve is connected to an arm 156, which, in turn is connected to a link 157. The link at its upper end is pivoted to the lever 158, which has a lateral projection 159, adapted to co-operate with the disk 160. This disk has a cam recess 161, 115 formed therein. The disk 160, is mounted on the shaft 162, which carries the sprocket wheels 102. As the shaft 162, rotates the damper will be intermittently operated remaining open while the projection 159, is 120 dropped into the cam recess 161, in the disk 160. When, however, this projection rides on the outer surface of the disk, the damper 125 is closed.

The endless conveyer is operated through 120

the rotation of the shaft 101. This shaft carries a clutch one section of which is indicated at 163. This section is loose on the shaft and carries a worm gear 164, which meshes with the driving worm on the vertical shaft 165. The vertical shaft 165, carries the bevel gear 166, at its upper end, which meshes with the bevel gear 167, on the main shaft driven by the belt wheel 85. As the main shaft rotates, the clutch member 163, will be rotated. Splined to the shaft 101, is the other clutch member 168. These clutch members are provided with interlocking teeth, which when in mesh positively cause the movements of the driving shaft to be transmitted to the shaft 101. A spring 169, normally operates to hold the clutch members in engagement. Mounted on the clutch member 168, is a collar 170, the side face of which is inclined as indicated at 171. A rod 172, is mounted in a suitable housing 173, and is normally spring-pressed towards the clutch members, by means of a spring 174. When the rod is in the position shown in Fig. XI, the clutch members are held separated and therefore the endless conveyer will be stopped. When the end of the rod is withdrawn, then the spring 169, will cause the clutch members to intermesh, and the shaft 101, will be rotated. Upon a half revolution of the shaft 101, the inclined collar will come to a point where the rod slides from its outer face and moves to its extreme inward position. On the next half rotation of the shaft the rod working against the inclined face of this collar, will force the outer clutch member back, opening the clutch and stopping the machine. Therefore the manual withdrawing of the rod starts the conveyer but said rod operates normally to automatically stop the conveyer after the shaft 101, has made one complete rotation. The stations for rinsing, sterilizing and drying are so disposed along the table that a single rotation of the shaft 101, will center the can over the nozzle first at the rinsing station, then center the can over the nozzle at the sterilizing station, when the shaft 101, is making its single rotation. On the next rotation of the shaft, the can will be moved to and centered over the drying outlet, and so on through to the end of the machine. The shaft 162, turns in unison with the shaft 101. The disk 160, is so positioned on the shaft 162, that when the conveyer is stopped the projection 159, drops into the cam recess, opening the valve, and permitting the hot air to pass through to the manifold 151. As soon as the conveyer starts, then this valve is closed, cutting off the air until the can and cover have been positioned at the next drying station. The air is heated in the chamber 146, by a series of steam coils 175, which are connected to steam manifolds 176, and 177. The steam manifold 176, is in turn connected through the pipe 178, with the intake steam pipe. The valve 118, controlling the steam supply to the injector is operated by a lever 179, which is weighted at 180. This lever at the outer end is connected with a vertical sliding rod 181, which runs in suitable guides. Said rod has a notch 182, formed therein which is adapted to engage a fixed lug 183, when in raised position. A spring 184, normally draws the rod 181, so as to cause the notch to engage this lug. The operator by raising the rod 181, opens the valve, and the spring 184, draws the rod into a locking engagement with the lug, and holds the valve open. The rod 172, is pivoted at its outer end to a lever 185. This lever is in turn fulcrumed at 186, on the frame and at its other end is connected by a link 187, to a hand lever 188, which is fulcrumed at 189. Said hand lever is formed with a handle 190, which is disposed at the front side of the machine, where it is readily accessible. This lever 188, extends through a guide 191, rigid with a bar 192. The bar 192, is pivoted at 193, and at the outer end is connected with the slide 194, having a foot piece or treadle 195. Said bar 192, is also provided with a pin 196, which is adapted to engage an inclined plate 197, fixed to the bar 181. By raising the hand lever 188, the rod 172, is withdrawn so as to permit the clutch members to close and the conveyer to be started. Whether this lever 188, be raised by hand or by the foot piece or treadle 195, the bar 192, will swing on its pivot 193. The pin 196, moving on the incline 197, will force the bar 181, to the left, at the upper end, releasing the same from its locking engagement with the lug 183, and this permits the same to drop, thus closing the valve 118. This ensures that the valve 118, be closed whenever the conveyer is started. The valve 118, is opened for washing, rinsing and sterilizing and may remain open, as long as desired, and as long as it is open the washing and rinsing water continue to flow. As soon however, as it is desired to move the can to another station, the operator only has to release the rod or bolt which holds the clutch members separated and the conveyer starts at once, and automatically stops when the can is positioned at the next station, and centered over the nozzle at said station. The operator then raises the valve and begins the next washing operation at the washing station. The can is placed over the brushes and is readily gripped between the holding arms through the release treadle 50, the spring causing the arms to close against the can. The can is raised and lowered through the lever 65, and may be raised or lowered to a limited extent, without stopping the rotat-

tion of the shaft 2. The throwing of the lever to a greater extent stops the shaft and then raises the can to the position to facilitate its removal. The operator through the treadle 50, may release the can so that it will rotate with the brushes and the outer face of the can washed.

From the above it will be apparent that we have provided a very simple washing machine wherein the can is thoroughly washed with brushes, the wash water supplied thereto through the steam injector or siphon, and the wash water continues to flow as long as the steam valve is open. The can may be quickly removed from the washing apparatus and placed on the table at the rinsing station. The same operation which starts the flow of the wash water for the next washing operation starts the rinsing water and the can and cover on the supporting table are thoroughly rinsed by the water which is thrown there against by the steam injector or siphon. The conveyer may be quickly started to move the can on to the next station to make room for the last washed can, and it will automatically stop when the cans are properly positioned and automatically turns on the drying air for drying the cans at the drying station. The supplies of steam to the injectors 124 and 140, and of wash and rinse water and sterilizing steam at the stations W, R, and S, are all controlled in unison by means of the steam valve 118; which is manually opened to turn them on (independently of the manual starting of the conveyor) by the means described above, and is automatically closed when the conveyor is started. The soda solution is fed from the tank 128 to the supply of wash water stored in the tank 126 while the conveyor is in operation, in preparation for the next turning on of the wash water for washing a can. The cans and covers are concurrently treated with fluid from beneath during their progression pari passu along the rods or rails of the trackways by the conveyer.

It is obvious that minor changes in the details of construction may be made without departing from the spirit of the invention as set forth in the appended claims.

Having thus described our invention, we claim:

1. A milk-can washing machine comprising, in combination, a washing station with means for washing the cans; a series of stations with means for rinsing, steam sterilizing, and air drying the washed cans; conveying means for presenting the cans successively at the stations of said series; manual means for independently starting the conveyor and turning on the washing and rinsing water and the sterilizing steam; means for automatically turning off the washing and rinsing water and the steriliz-

ing steam when the conveyor is started; means for stopping the conveyor; and means for automatically turning off and on the drying air when the conveyor is started and stopped respectively.

2. A milk-can washing machine comprising, in combination, a washing station with means for washing the cans; a series of stations with means for rinsing, steam sterilizing, and air drying the washed cans; conveying means for presenting the cans successively at the stations of said series; manual means for independently starting the conveyor and turning on the washing and rinsing water and the sterilizing steam; means for stopping the conveyor; and means for automatically turning off and on the drying air when the conveyor is started and stopped respectively.

3. A milk-can washing machine comprising, in combination, a washing station with means for washing the cans; a series of stations with means for rinsing, steam sterilizing, and air drying the washed cans; conveying means for presenting the cans successively at the stations of said series; manual means for independently starting the conveyor and turning on the washing and rinsing water and the sterilizing steam; and means for automatically turning off the washing and rinsing water and the sterilizing steam when the conveyor is started.

4. A milk-can washing machine comprising, in combination, a washing station with means for washing the cans; a series of stations with means for rinsing and steam sterilizing the washed cans; conveying means for presenting the cans successively at the stations of said series; manual means for independently starting the conveyor and turning on the washing and rinsing water and the sterilizing steam; and means for automatically turning off the washing and rinsing water and the sterilizing steam when the conveyor is started.

5. A milk-can washing machine comprising, in combination, a washing station with means for washing the cans; a series of stations with means for treating with fluid the washed cans; conveying means for presenting the cans successively at the stations of said series; manual means for independently starting the conveyor and turning on the washing water and the treating fluid; and means for automatically turning off the washing water and the treating fluid when the conveyor is started.

6. A milk-can washing machine comprising, in combination, a washing station with means for washing the cans; a series of stations with means for rinsing and steam sterilizing the washed cans; conveying means for presenting the cans successively at the stations of said series; means for automatically turning off the washing and rinsing

- water and the sterilizing steam when the conveyor is started; and means for feeding soda solution to the wash water while the conveyor is in operation.
- 5 7. A milk-can washing machine comprising, in combination, a washing station, and a series including a rinsing station and a steam sterilizing station; conveying means for presenting the cans successively at the stations of said series; steam injectors for supplying washing and rinsing water at said washing and rinsing stations; valve means for controlling in unison the steam supply to said injectors and to said steam sterilizing station; manual means for independently starting the conveyor and opening said valve means; and means for automatically closing said valve means when the conveyor is started.
- 10 8. A milk-can washing machine comprising, in combination, a washing station, a rinsing station and a steam sterilizing station; steam injectors for supplying washing and rinsing water at said washing and rinsing stations; and valve means for controlling in unison the steam supply to said injectors and to said steam sterilizing station.
- 15 9. A milk-can washing machine comprising, in combination, a series of stations with means for rinsing, sterilizing, and drying the interior of the cans from beneath and for concurrently washing the corresponding can covers inside and out and sterilizing and drying said covers from beneath; and conveying means for presenting cans inverted and their corresponding covers right side up concurrently at the successive stations.
- 20 10. A milk-can washing machine comprising, in combination, a supporting way; an endless conveyor with means for moving cans inverted and their corresponding covers right side up pari passu along said way; and means for concurrently treating the interiors of corresponding cans and covers with fluid from beneath during their progress along the way.
- 25 11. A milk-can washing machine comprising a way with a series of longitudinal supporting members; an endless conveyor comprising chains travelling lengthwise of said members with transverse cross-pieces connected thereto adapted to engage cans inverted and their corresponding covers right side up and slide them pari passu along said members; and means for treating the interiors of the cans and covers with fluid from beneath during their progression along the rods by the conveyor.
- 30 In testimony whereof, we have hereunto signed our names at Philadelphia, Pennsylvania, this seventeenth day of May, 1917.
